UNITED STATES PATENT OFFICE.

RAOUL FEIGNOUX, OF MONTREUIL-SOUS-BOIS, FRANCE.

VIAL FOR MEDICINAL AND LABORATORY PREPARATIONS.

1,202,497.

Specification of Letters Patent.

Patented Oct. 24, 1916.

Application filed June 15, 1914, Serial No. 845,252. Renewed September 19, 1916. Serial No. 121,095.

To all whom it may concern:

Be it known that I, RAOUL FEIGNOUX, a citizen of the Republic of France, residing in Montreuil-sous-Bois, France, have invented certain new and useful Improvements in Vials for Medicinal and Laboratory Preparations, of which the following is a specification.

Numerous pharmaceutical preparations and remedial substances, and particularly serums for hypodermic treatment are placed on the market in a perfectly sterile condition, in glass vials having usually two ends each drawn to a point and sealed. At the moment of using the preparation or remedial substance, one of the sealed points is broken by the user for the purpose of inserting therein the needle of a syringe and then drawing in by suction the contents of the vial into the syringe. In spite of all precautions and expedients for insuring asepsis which are generally adopted in disinfecting or sterilizing the syringe and passing the needle through a flame, cases of infection of the treated tissues of the patient have frequently occurred due to the introduction of pathogenic germs during the injecting operation.

It was soon discovered that the infecting of the preparation or remedial substance was caused by the bubbles of air passing into the vial for the purpose of replacing the liquid preparation drawn into the syringe in charging the latter. This charging is done usually in the sick chamber or in the hospital ward or operating theater, where the atmosphere is loaded with microbes and pathogenic germs and, therefore, it is obvious that the air bubbles entering through the broken point of the vial in counterflow of the liquid preparation which is being drawn into the syringe, and which pass completely through the said liquid, must necessarily carry pathogenic germs into the midst of the said liquid preparation, thereby utterly destroying all the aseptic precautions, and the more so, the larger the capacity of the vial. With the object of remedying these drawbacks, which are extremely serious from both medical and surgical points of view, various types of self-injecting vials have been proposed which enable the preparation, remedial substance or serum to pass directly through the end of the vial into the tissues of the patient, with the object of avoiding the risk of in-

fecting the liquid preparation by having to pass first through a syringe.

Vials of that type are, however, attended by numerous difficulties in use, namely: They are more delicate and complicated to handle, and they require rather more skill and experience, and further they are very dear, while they do not allow the use of ordinary syringes.

Now the present invention has for its object to provide an improved vial for serums and the like, which shall solve completely the problem of insuring an absolutely perfect asepsis, by obviating all bubbling up of the air through the serum, and which shall also be capable of being used with any type of syringe. The improved vial is extremely simple in construction without however requiring any change in the usual method of operating.

This invention is illustrated by way of example in the accompanying drawing, in which:

Figure 1 is a side elevation of an improved vial of the cylindrical tube type, and Fig. 2 is a side elevation, illustrating the same vial in use with a syringe during the operation of transferring the serum or the like from the vial into the syringe.

The improved vial consists of a suitable glass container *a* which may be of cylindrical form as shown, or of any other suitable form, for instance, pearshaped, ovoid, etc., according to the quantity of serum to be contained. It has at its upper end an ordinary point *b*, which has been drawn fine and sealed by means of a blowpipe flame, and at its lower end a slender tubular extension *c*, which has been folded back vertically along the side of the container *a*. This tubular extension is likewise drawn to a fine point and preferably sealed by means of a blowpipe flame. The processes for charging the improved vial and sterilizing its contents in the digester are the same as for ordinary vials.

To use the improved vial, the points of its ends *b* and *c* are broken, and the needle of the syringe *d* is inserted into the hole in the extension *c*, which is thus completely closed up by the needle. The suction of the syringe will then cause the serum to rise in the syringe, while the level of the serum in the container *a* will fall accordingly. Air will enter through the broken point *b* in the di-

rection of the arrow and will fill the space left by the serum at the same rate as the latter is sucked away by the syringe, but without any risk of the air bubbling through the serum, so that there is no possibility of the serum becoming infected thereby.

As usual, the whole of the serum is not drawn to the last drop into the syringe, so that the portion of serum which has come in direct contact with the air will remain in the vial, and is further separated from the outside air by a certain quantity of sterilized air remaining in the vial. By this means the serum or the like has been transferred into the syringe under exactly the same conditions of asepsis as it was while contained in the vial.

Having now particularly described and ascertained the nature of my said invention,

20 I declare that what I claim is:

1. A vial for serum and the like, comprising in combination with the wide container for the serum, a pointed upper end and a pointed lower end of restricted cross section bent back upon said container and adapted to have its point broken off for the recep-

tion of a serum, said point at the upper end being also adapted to be broken off for admitting air at that level of the serum not being fed into the syringe, substantially as 30 described.

2. A vial for serum and the like for preventing infection of the serum during the transmission of the latter into a needle syringe comprising a wide container having two sealed pointed ends, one of which has the form of a fine bore a tubular extension of restricted cross section bent back upon the side of the container, into which extension when the point is broken, the needle of a syringe can be inserted for drawing up the serum or the like, the other end adapted to be broken off for admitting air to that level of the serum not to be fed into the syringe.

45 In testimony whereof I affix my signature in presence of two witnesses.

RAOUL FEIGNOUX.

Witnesses:

CHAS. P. PRESSLY,
EDWARD WOLF.
